UNITED STATES PATENT OFFICE.

RALPH W. ATKINSON, OF PERTH AMBOY, NEW JERSEY, ASSIGNOR TO STANDARD UNDERGROUND CABLE COMPANY, OF PITTSBURGH, PENNSYLVANIA, A CORPORATION OF PENNSYLVANIA.

CABLE JOINT.

Application filed November 26, 1924. Serial No. 752,357.

To all whom it may concern:

Be it known that I, RALPH W. ATKINSON, residing at Perth Amboy, in the county of Middlesex and State of New Jersey, a citizen of the United States, have invented or discovered certain new and useful Improvements in Cable Joints, of which improvements the following is a specification.

My invention relates to improvements in the structure of joints for electric cables, and consists in a structure, in which electrostatic strain is distributed over extended surfaces, and the surfaces themselves are so perfectly insulated, as to remove and make remote the danger of breakdown. My invention accordingly becomes of great practical value in the installation of high-tension cables.

The invention is a specific carrying into practice of that invention of Donald M. Simons which is described in a co-pending application of Simons, filed November 19, 1924, Serial No. 750,740.

In two other pending applications of the said Simons, one of them filed September 18, 1924, Serial No. 738,424, and the other filed October 15, 1924, Serial No. 743,645, the generic invention of the said Simons is described in its adaptation to a cable joint, particularly in protecting the cut-away end of the cable-sheath, and in preventing breakdown at that point. My present invention is found in the adaptation of the same generic invention to a cable joint, but at another point: it is the joined conductors which I protect.

My invention is illustrated in the accompanying drawings, in which Fig. I shows diagrammatically and on a medial and longitudinal section a cable-joint, in the structure of which the invention is embodied. Fig. II is a diagrammatic view in plan of a sheet of material employed in the building of the joint of Fig. I.

Fig. I shows two cable-ends, from which the envelope 1 of machine-laid insulation, and the sheath 4, have been cut away, to progressively greater distances, and whose bared conductor-ends 2 have been electrically united within the sweated-on metallic sleeve 3.

Such a union is ordinarily wrapped in paper or equivalent material, and then a joint-casing is brought to place, enclosing the whole; the joint-casing is at its ends secured to the cable-sheath, and then the structure within is flushed and the spaces within are filled with insulating compound. The problem is to protect the actual joint, and to prevent break-down from the conductor-union, through whatever dielectric may lie between, and to an adjacent metallic body. The conductor union is a point within the structure where great concentration of stress occurs, and breakdown must be prevented by dielectric material of great strength properly applied.

My invention is achieved by wrapping upon the joined cable-ends a web of suitable insulating material, such as paper, which preferably in a single wrap shall form around the joined conductor-ends the insulating envelope 5. This wrapped-on web of paper is provided with a strip of metal, and the strip of metal is so disposed upon the web of paper that, when the paper has been applied, the metal will form the body 6, incorporated with the body 5 of wrapped-on paper.

The step of procedure just indicated will be understood on comparing Fig. II with Fig. I. Fig. II shows the web of paper 9 in plan, with the strip of metal 8 in place upon it, and the position of Fig. II relatively to Fig. I is such as to indicate the position in which application is made. The strip 8 extends to that edge of the web of paper which is first applied, or substantially to the edge, and in consequence the metallic body 6 is, in the structure when built, electrically continuous with the cable conductors 2. Fig. II shows the strip extending toward the remote or last applied edge of the web of paper, but not reaching the edge. Accordingly, in the finished structure the metallic body 6 is wholly embedded within the envelope 5 of solid insulation. If the strip extended to this remote edge of the web, as it may, the body 6 would come medially to the surface of the body 5. In that case the body 6 would on its medial cross-section be of maximum permissible di-

2
ameter, and its equatorial radius on that medial plane would be at maximum.

Considering now the resultant structure, it will be perceived that, electrically regarded, the surface of the union 2, 2, 3 has been extended and that the strains tending to breakdown instead of being concentrated at the stepped edge of the sleeve 3, have been dissipated over the extended and

- 10 gradually curving surface of the body 6. And it will be observed further that, simultaneously with this extension of conductor surface, the superstructure of conducting material has been incorporated with a body 15 of solid insulation, in such manner that the meeting of surfaces, as between conductor and insulation, is exact and complete: there is no inter-surface space, where sparking and glowing might occur.

- 20 By the particular placement of the strip of metal upon the web of paper, the shape of the enlargement 6 of the conductor is variable and determinable. Fig. I shows the shape to be that of a hollow ellipsoid, surrounding the joint and electrically continuous with the cable-ends adjacent the joint. And, manifestly, the ellipsoidal surface so produced, embedded as it is in the solid insulation, effects a wide and even distribution of strain; this in a structure contained within an intimately enveloping body of insulation, highly resistant to the strains exerted.

- 25 The web 9 will ordinarily be of paper. It 30 may be formed of equivalent material, muslin, for instance, and it will ordinarily be filled with a suitable insulating compound, such as oil or varnish. The body built up of such material is, in its electrical character, 35 a solid body, as distinguished from a body of liquid insulation, which in its very nature is not suited to withstand the strains with which we here are concerned.

- 40 The metal strip 8 borne by the web of paper or equivalent material may be variously applied: it may be painted on the sheet, or sprayed on, or it may be applied in the form of foil. The sheet may itself be cut to receive the metal in the form of an inlay. 45 The strip of metal may be carried on one side of the web only or on both sides or may form a section of the web, continuous from surface to surface. If it be formed by application to opposite surfaces, the two applications may be made electrically continuous by penetration through holes in the web of paper.

- 50 Ordinarily in the wrapping on of the web the successive turns of the strip will make 55 contact turn upon turn, but this is not necessary: an attenuated spiral will have the same effect as a built-up ellipsoid, continuous on every meridian. It is requisite only that the body of metal be sufficient to endure under 60 service conditions.

Preferably, as I have said, the body 5 is built as a single wrap, in which the spirally laid laminations extend from end to end of the so-built structure.

I show the cut-away ends of the machine-laid insulation 1 to be stepped, and I show the edges of web 9 to be correspondingly cut, so that the edge of the wrapped-on body 5 makes snug contact with the stepped ends of the machine-laid insulation. Such minute 70 shaping of the parts results in a structure which manifestly is strong to endure service. It should however be remarked that in this particular the showing is exemplary, merely; my invention lies elsewhere, and the shaping 75 of the ends of the bodies 1 and 5, in steps or otherwise, with immediate surface-to-surface contact or not, is a matter in which the engineer may exercise his choice, suiting his work in this respect to conditions of installation and of service.

The body 5 having been built, the joint is in other respects completed in suitable manner. It may be wrapped with paper and enclosed in the usual joint-casing indicated in 80 dotted lines at 10, Fig. I, and then the structure within the casing may be flushed and all the spaces filled with insulating compound. The use of the invention in building the body 5 upon the joined conductor does not forbid its further use in providing the cut-away ends 4 of the cable-sheath with extensions, as set forth in Simons's prior applications, mentioned above.

The proportions given in the drawings are 85 necessarily far from those which actually will obtain, and in this respect the drawings are diagrammatic. The number of turns in building the body 5 is in practice greater than the drawings suggest. The web may 90 be very long, and the convergence of the opposite portions of strip 8, so clearly indicated in Fig. II, will in practical embodiment be beyond detection by casual inspection. In such matters the drawings of necessity are not to be taken as literal presentations of the structure.

The particular shape of the body 6 developed within the wrapped-on insulation 95 may be varied greatly, and will in its minute shape be suited to the conditions of service contemplated.

It will be understood, without particular illustration, that the invention is applicable, without any change whatever, to each of the conductors of a multiple-conductor cable, as well as to the single-conductor cable shown,

The wrap is preferably a single web, and in making installation, the application of it may readily be done in the field.

I claim as my invention:

1. In a joint structure for electric cables, a wrapped-on body of solid insulation enveloping the joined conductors and carrying 100 embedded within it a metallic shell in elec-

tric union with the conductor-ends adjacent their point of union.

2. In a joint structure for electric cables, a wrapped-on body of solid insulation enveloping the joined conductors, within which each convolution extends unbroken from end to end of the envelope, said body carrying

embedded within it a metallic shell in electrical union with the conductor-ends adjacent their point of union.

In testimony whereof I have hereunto set my hand.

RALPH W. ATKINSON.
